UNITED STATES PATENT OFFICE.

JOHN H. PARMELEE, OF BRIDGEPORT, CONNECTICUT, ASSIGNOR OF ONE-HALF TO AARON W. WALLACE, OF BRIDGEPORT, CONNECTICUT.

HAME-FASTENER.

SPECIFICATION forming part of Letters Patent No. 723,298, dated March 24, 1903.

Application filed January 20, 1902. Serial No. 90,511. (No model.)

To all whom it may concern:

Be it known that I, JOHN H. PARMELEE, a citizen of the United States, residing at Bridgeport, in the county of Fairfield and 5 State of Connecticut, have invented certain new and useful Improvements in Hame-Fasteners; and I do hereby declare the following to be a full, clear, and exact description of the invention, such as will enable others skilled 10 in the art to which it appertains to make and use the same.

My invention relates to certain new and useful improvements in hame-fasteners, and has for its object to provide a device of this 15 character in which the locking and unlocking of the parts are readily effected, while at the same time my improved fastening will be flexible, so as to adapt itself to the contour of the hame-collar.

20 With these ends in view my invention consists in certain details of construction and combination of parts, such as will be herein-after fully described and then specifically be designated by the claim.

25 In the accompanying drawings, which form a part of this application, Figure 1 is a broken perspective showing the parts of my improvement detached from each other and connected with the hame-eyes; Fig. 2, a similar view, 30 but showing my improvement in locked condition; Fig. 3, a detail perspective of the hame-loop and locking-lever, showing the position which said lever assumes when the parts are unlocked; and Fig. 4, a view similar 35 to Fig. 3, but showing the position assumed by the locking-lever when the parts are locked.

Similar numbers of reference denote like parts in the several figures of the drawings.

Heretofore hame-fasteners have been provided in which one element consisted of a short section of chain connected with one of the hame-eyes, while the other element consisted of a locking-lever connected with the other hame-eye either directly or through 45 the medium of any suitable link or loop; but all of these constructions required a special locking ring or loop, which engaged with the end of the locking-lever, so as to hold the latter in position when the hames were fastened.

50 My improvement consists of a single lock-

ing-lever so constructed and pivoted that no auxiliary device is required for holding the hames fastened, while at the same time the greater the strain put upon the hames the less is the tendency of the lever to drop to its unlocked position.

55 1 2 are the usual hame-eyes; 3, a short section of chain having at one end a hook element 4, which latter is attached to the hame-eye 2, and 5 is what I term a "hame-loop," which is provided with hooks 6 at one end, which are connected with the eye 1, while the other end of said loop is curved and slightly bent downward.

60 7 is the locking-lever, one end of which is formed into an eye 8, which embraces the free end of the loop 5, so as to afford a pivotal support for said lever. Adjoining this eye the lever is deflected laterally, as shown 65 at 9, and then bent so as to form a bight 10, the remaining portion or free end of the lever being straight and substantially parallel with the plane of the eye 8. It will thus be readily understood that the eye 8 and bight 10 extend in the same direction substantially as 70 the lever 7, so that when the lever is brought into locking position, as shown at Fig. 2, said eye and bight will extend in a horizontal plane.

75 In utilizing my improvement the lever 7 is passed through one of the links of the chain 3 and then forced outwardly toward the under side of the loop 5, and when the bight 10 has been thus brought into nearly horizontal 80 alignment with the eye 8 the chain-link will have been brought into the extreme end of the bight 10, and a strain will therefore be exerted which will cause the lever to automatically assume its locked position. In 85 fact, this strain on the lever will keep the latter firmly in locked position, so that if the lever should be withdrawn a short distance and released it will immediately return to locked position with a resilient action. The 90 deflection 9 causes the eye 8 to be separated from the body of the lever by a space sufficient to admit the chain-link to the bight 10; but this deflection also enables the lever in locked position to conform more closely to 95 the shape of the hame-collar. In unfastening the hames the lever is pulled downwardly 100

until the link of the chain passes beyond the bight, when the parts will readily separate and assume the position shown at Fig. 1.

Having thus described my invention, what I claim as new, and desire to secure by Letters Patent, is—

In a hame-fastener, the combination of the loop connected to one of the hame-eyes, the locking-lever having one extremity bent backward and deflected to one side to form a bight and terminating in an eye at the end

of the deflected portion, said eye loosely embracing the inner bar of said loop, and a suitable chain secured to the other hame-eye, substantially as set forth.

In testimony whereof I affix my signature in presence of two witnesses.

JOHN H. PARMELEE.
